UNITED STATES PATENT OFFICE.

FRANK WEBB STOCKTON, OF CHICAGO, ILLINOIS.

MULTIPLE-TOWEL HOLDER.

1,241,778.

Specification of Letters Patent.

Patented Oct. 2, 1917.

Application filed June 16, 1916. Serial No. 104,134.

To all whom it may concern:

Be it known that I, FRANK WEBB STOCKTON, a citizen of the United States, residing at Chicago, in the county of Cook and State 5 of Illinois, have invented new and useful Improvements in Multiple-Towel Holders, of which the following is a specification.

One of the objects of my invention is to provide an improved device for supplying 10 individual towels for public use, successively to respective users. Another object is to provide means in such device for the disposal of soiled towels. Another object is to provide in such device, means tending to 15 prevent the misplacement of the towels before or after use. Another object is to provide in such device means tending to especially convenient use. Another object is to provide such a device as will be especially 20 simple and cheap. Other objects will be evident hereinafter.

Referring to the drawings, Figures 1, 3, 25 4, and 6 are perspective views of several devices for this purpose. Fig. 2 is a vertical, front-to-back, middle section of the device shown in Fig. 1. All these figures illustrate cabinet styles. Figs. 7, 8, 9, 10, 11, 12, and 30 13 are perspective views of such devices made of heavy wire and other simple parts. Fig. 5 is a perspective view of a towel. Fig. 14 is a vertical, front-to-back, middle sectional view showing a method of suspending towels. Similar numerals refer to similar parts throughout the several views.

The device comprises an upper supporting bar or elongated member 2 over which the clean towels 4 are hung or folded; a lower receptacle 3 for containing soiled towels; and a retaining rod 1 extending 35 from the upper bar to the lower receptacle. In Figs. 7, 8, 9, 10, 11, 12, 13, and 14, the lower receptacle such as is shown at 3 in Figs. 1, 2, 3, 4, and 6 is not included in the device as shown. The towels are strung on the retaining rod 1, and for this purpose each towel has at one edge a hole which is reinforced by a gromet 7, the hole being large enough to allow the towel to be easily slipped along the rod. As shown at 6, Fig. 50 2, the lower end of the retaining rod 1 is bent forward and fits the hole made for it in such a way as to be secure against removal unless rod 1 is leaned forward, in which case, it can be slipped out. As shown 55 at 5, the upper end of the retaining rod is secured, and in the normal working position

neither end of the rod can be removed. In Figs. 7, 8, 9, 10, 11, 12, and 14, the upper end of the retaining rod 1 is shown permanently attached to the supporting bar 2; 60 but if desired the connection can be made such as to afford convenient disconnection. In Figs. 7, 8, 9, 10, 11, 12, 13, and 14, at 6, are shown means for attaching rod 1 to a desired object in such a way as to afford 65 convenient disconnection. In Fig. 13 the retaining rod 1 does not touch the supporting bar 2, but has means for attachment to other suitable objects of support.

In Figs. 1, 2, 6 and 14, the upper portion 70 of the retaining rod 1 extends horizontally outwardly from the suspending bar 2 and then downwardly. In Fig. 3 it extends upwardly therefrom, then outwardly and then downwardly. In Figs. 4, 10, and 11 it extends downwardly therefrom, then outwardly and then downwardly. In Fig. 8 the retaining rod 1 first extends downwardly a comparatively short distance, then horizontally outwardly and then downwardly. 75 This first small downward extension in Fig. 8 is for the purpose of placing the horizontal, outward extension of rod 1 at a slightly lower level than the suspending bar 2, thus modifying the form of a bundle of 80 towels hung over bar 2. In Fig. 9 the retaining rod 1 extends from the suspending bar 2 first slightly down and then slightly out; then upwardly, outwardly, and downwardly. These first slight down and out extensions are for the purpose of placing the upward extension of rod 1 a short distance out from bar 2. In Fig. 12 the retaining rod 1 extends from suspending bar 2 first 85 slightly rearwardly then upwardly, outwardly, and downwardly. The first small rearward extension is for the purpose of placing the upward extension of rod 1 a short distance back from the suspending bar 2, thus modifying the form of a bundle of 90 towels suspended over bar 2. In Fig. 12 at numeral 12 is shown a short projection from the retaining rod 1, which serves the purpose of preventing the gromets of the towels 95 from slipping down past that point while 100 lying over bar 2. In all the devices the retaining rod 1 can have a similar projection or other means to prevent the gromets from slipping all the way to the suspending bar 2. In Fig. 13 the retaining rod 1 extends 105 from its point of attachment at 5 outwardly over bar 2 and then downwardly. In Fig.

13 the retaining rod 1 can be made to extend from an attachment as at 5 outwardly and below suspending bar 2.

The retaining rod 1 in any case need not extend precisely horizontally or perpendicular from the supporting bar 2 but may be inclined in any direction. In Fig. 7 the retaining rod 1 extends outwardly from the supporting bar 2 at an upward inclination to the horizontal.

In Figs. 1, 2, 3, 4, and 6 the supporting bar 2 is supported in position by means of bars, standards or both. In Figs. 7, 9, 10, 11, 12, 13, and 14, the suspending bar 2 is supported in position by simple members which are themselves attached to other objects for support. In Figs. 7, 9, 10, 11, 12, and 14, the retaining rod 1 may help support bar 2. In Fig. 8, bar 2 is entirely supported by rod 1. In Fig. 13 the support of suspending bar 2 is independent of rod 1.

In Figs. 1, 3, and 4 are shown in perspective methods of hanging a towel 4 over the supporting bar 2 and attaching said towel to retaining rod 1. Only a single towel is shown in these three views and it is assumed to be somewhat transparent in order not to hide the structure beneath. In Fig. 2 is shown in section a method of hanging a large bundle of towels over the supporting bar 2, the towels being retained on the rod 1 by their gromets 7. For the sake of clearness only three of the towels of the bundle are actually indicated by the lines of the figure. The intervening spaces are assumed to be filled with towels so as to form a compact bundle. It will be seen that if the towels are of equal length, it is necessary to fold the inner, lower ones back and forth several times in order that the lower ends may be even. In the method of suspending the towels as shown, they extend from rod 1 over bar 2 and hang down back of bar 2. Instead, in many of the devices they can be folded from rod 1 over bar 2, hanging down in front of bar 2. The device of Fig. 12 is designed for this forward hanging of the towels. Here the towels hang from the upward extension of rod 1 forward, over, and in front of bar 2. Also, the device of Fig. 13 is designed for hanging the towels so that their downwardly extending ends hang forwardly over the suspending bar 2. In the device of Fig. 13 the towels hang from the upwardly inclined portion of rod 1 downwardly, forwardly, and over bar 2. In Fig. 14 is shown in section a method of hanging towels wherein alternate towels hang downward from the retaining rod 1 and the other towels hang back over bar 2. In this method the towels hanging back over bar 2 prevent the towels hanging directly downward from becoming disordered, to a considerable extent.

65 The devices shown in Figs. 6, 7, and 8

are adapted to the method of hanging and retaining towels shown in Figs. 1 and 2. The device of Fig. 9 is adapted to the method of hanging and retaining towels shown in Fig. 3. The devices of Figs. 10 and 11 are 70 adapted to the method of hanging and retaining towels shown in Fig. 4.

In order to facilitate the work of stringing the towels upon the retaining rod 1 and hanging them upon the clean-towel suspending bar 2, it is well first to form a bundle of them of such shape as to fit the given towel-holder. This may be done at the laundry, and is accomplished by hanging the towels upon a suitable form having a shape similar to that of the given towel-holder, and provided with a short rod extending from the form as the retaining rod extends from the suspending bar of the towel-holder. In using the form, the gromet of a towel is placed on the short rod with the towel extending outwardly therefrom. The towel is then folded over the form in a position corresponding with the position it will occupy on the suspending bar of the towel-holder. Other towels are treated likewise until a bundle of towels of the desired size and shape is built up. Then the bundle is firmly bound in this shape by cord and is removed from the form. In order to keep the holes of the towels in line a wooden stick may now be passed through them and bound in place. Such a bundle may be transported and conveniently placed on the retaining rod of a towel-holder and in position on the suspending bar thereof.

In order to remove soiled towels and replace clean towels in the devices of Figs. 1, 2, 3, 4, 6, and 13, the upper end of the retaining rod is unlocked or disconnected at 5, the rod is leaned forward and lifted out, when the soiled towels will fall off the lower end. The lower end is then replaced in its fastening, shown at 6, Figs. 2 and 13, and a bundle of towels is suitably placed on the retaining rod by way of its upper end. The upper end is then secured at 5 and the bundle of towels is laid over the suspending bar 2.

To remove soiled and replace clean towels in the cases shown in Figs. 7, 8, 9, 10, 11, 12, and 14, the lower end of the retaining rod 1 is disconnected at 6 and moved forward. The soiled towels are slipped off and the bundle of clean towels slipped on and moved to position over the suspending bar 2.

In Figs. 1, 2, 3, 4, 7, 9, and 11, the members supporting the suspending bar 2 help to hold the towels in place as they hang over bar 2. In Figs. 6, 7, 8, and 10, members designated by reference numeral 8, are provided for this purpose. In Fig. 7 these upright members marked 8 may be omitted.

In Fig. 9 at reference numeral 9 is shown the supporting member for bar 2 as having 130

a perpendicularly wavy, spring-like form. The purpose of this is to facilitate the outward springing of rod 1 after disconnection at 6 for changing the towels. This object is 5 accomplished in Fig. 11 by making the suspending bar 2 rotatably connected, as shown at 10, to its supporting members, which support it from above. In order to facilitate the connection and disconnection 10 of rod 1 at its lower end, a portion of the lower end may be made of chain with a rod on its end for convenient insertion through the gromets of the towels and attachment to a support.

15 In Fig. 9 at 11 is shown a member extending horizontally a short distance below the suspending bar 2. This member 11 is intended to prevent a person from attempting to withdraw a towel from beneath bar 2 instead of from over the top which is the correct way. If the towels are hung forwardly over bar 2, then member 11 does not serve the purpose just named. In the case 20 of the forward hanging of the towels there 25 is less chance of a person attempting to withdraw a towel the wrong way. Member 11 also serves the purpose of steadyng the bundle of towels hanging over bar 2.

It will be observed that the towel-holders 30 of Figs. 7 and 10 can be constructed practically entirely of a single, continuous piece of heavy wire.

For public use a large number, say one hundred, clean towels are hung in position 35 on the suspending bar 2 with their gromets strung on the retaining rod 1. A person desiring to use a towel, grasps the top towel, pulls it forward on the retaining rod 1 in the direction indicated by the arrows to a position convenient for use, where it can be used for the hands or face. After use the

towel is released and it drops by its weight into the soiled-towel receptacle 3, as in some of the devices, or to the lower end of the retaining rod 1, all the while following the 45 course of the retaining rod.

While I have described particular constructions as specific embodiments of my invention, I desire not to be limited thereto.

What I claim and desire to secure by 50 Letters Patent is:

1. In a device of the class described, a narrow, elongated, suspending member, adapted to suspend a towel by a narrow, median portion thereby allowing its ends to hang 55 downward over the sides of said suspending member; and an elongated retaining member, adapted to retain towels attached thereto and to guide the towels from the suspending member to a point convenient for use 60 and then downwardly, said retaining member extending from a point midway between the ends of the suspending member in a plane at an angle to the suspending member, substantially as described. 65

2. In a device of the class described, a towel-suspending member and a towel-retaining member, said device being adapted for the attachment of a towel to the retaining member and its suspension over the 70 towel-suspending member, the towel-retaining member extending outwardly from said suspending member and then downwardly sufficiently to constitute a suitable guide for a towel while in use, substantially as described. 75

In testimony whereof, I have subscribed my name.

FRANK WEBB STOCKTON.
